(57) **CLAIM**

The ornamental design for a golf training aid, as shown and described.

DESCRIPTION

FIG. 1 is a perspective view of the golf training aid showing my new design.

FIG. 2 is a top plan view of the golf training aid.

FIG. 3 is a bottom plan view of the golf training aid.

FIG. 4 is a left side elevation view of the golf training aid.

FIG. 5 is a right side elevation view of the golf training aid.

FIG. 6 is a rear end elevation view of the golf training aid.

FIG. 7 is a front end elevation view of the golf training aid; and,

FIG. 8 is a perspective view of an alternate positioning of the golf training aid.

1 Claim, 6 Drawing Sheets
